UNITED STATES PATENT OFFICE.

JOHN ROBERT TOMLIN, OF BROOKLYN, NEW YORK, ASSIGNOR TO INTERTYPE CORPORATION, OF BROOKLYN, NEW YORK, A CORPORATION OF NEW YORK.

TYPOGRAPHICAL MACHINE (CHANNEL ENTRANCE).

Application filed July 1, 1926. Serial No. 119,905.

The present invention relates to improvements in typographical machines of the general class shown and described in U. S. Letters Patent No. 436,532, granted September 16, 1890, and it is more particularly applicable to machines of this general class which are constructed to hold two or more magazines which may contain, respectively, matrices belonging to different fonts or matrices having different kinds or styles of type faces, and from which magazine matrices may be drawn as desired and assembled to form a line of mixed matrices from which type bars or slugs may be cast, machines of this class being known as of the mixer type. The invention relates especially to machines of this type in which the magazines are mounted to rock or tilt rearwardly in order to permit removal of the magazines at the rear of the machine, and in which channel entrances are positioned between the magazines and the distributor mechanism, when the magazines are in their normal or operative position, to guide the matrices returning from the casting mechanism from the distributor mechanism to the magazines.

In machines of this type, the upper portion of the channel entrance must be positioned at a predetermined distance below the distributor screws, and the lower portion of the channel entrance must engage and register with the upper rear ends of the magazines when the latter are in their normal forwardly and downwardly inclined position. When it is desired to tilt the magazines rearwardly for magazine removal or to examine the distributing mechanism or the interior of the channel entrance, it is necessary to first move the channel entrance from its normal position, but since the upper terminals of the channel entrance, when the latter is in its normal position, is disposed immediately adjacent to the lower distributor screws, it has heretofore been difficult to remove the entrance without interference from other parts or mechanisms of the machine, because the entrance must first be moved sharply downwardly to avoid striking the lower distributor screws, and the entrance must immediately thereafter move rearwardly away from the magazines in order that the magazines may clear the entrance when they are rocked or tilted rear-

wardly and downwardly to bring them into 55 magazine-removing position.

The primary object of the present invention is to provide a novel and improved channel entrance and mounting therefor which overcomes the difficulties or objections 60 which have been experienced with channel entrances which have been heretofore used on machines containing rearwardly tilttable magazines, the channel entrance and its mounting, according to the present invention, enabling the channel entrance to be easily and quickly moved out of its operative position without interference from or interfering with the distributor screws, and then movable out of the path of the upper 65 ends of the magazines so that the latter may be swung or rocked rearwardly without interference from the channel entrance; or the channel entrance may be easily and quickly removed from its operative position to a 70 position which enables the distributor mechanism or the channel entrance to be inspected or renders the distributing mechanism and the channel entrance accessible, for removal of obstructing matrices, repair or 75 other purposes.

Another object of the invention is to provide a novel and improved channel entrance and mounting therefor, together with means which enables the channel entrance to be 80 easily and quickly moved from its operative position to one position which enables the magazines to be swung rearwardly to magazine removing position and which enables the channel entrance to be moved, when desired, to a second position which affords easier access to the distributing mechanism and the assembler entrance and will effect removal of any matrices that may clog the channel entrance, a simple controlling device 85 being provided which determines which of these positions will be assumed by the channel entrance when it is moved from its normal operative position.

Another object of the invention is to provide a composite frame which constitutes the mounting for the channel entrance whereby the desired movements are obtained, together with means which serves to counter-balance the channel entrance and its mounting and to normally hold the components of the mounting in proper relationship when the channel entrance occupies its 100 105

operative position, thereby enabling the channel entrance to be manipulated with ease, speed and facility.

To these and other ends, the invention ⁵ consists in certain improvements and combinations and arrangements of parts, all as will be hereinafter more fully described, the features of novelty being pointed out particularly in the claims at the end of the ¹⁰ specification.

The preferred embodiments of the invention are shown in the accompanying drawings, wherein:—

Figure 1 is a side elevation of the upper ¹⁵ portion of a typographical machine of the type hereinbefore referred to and to which the present invention is applied, parts being broken away or shown in section.

Figure 2 is a side elevation, partly in section, of the improved channel entrance and its mounting, the dotted lines showing the position of the upper end of the channel entrance relative to the distributing mechanism when the entrance is in its normal ²⁰ operative position and the full lines showing the position into which the entrance is first moved to remove it from operative position.

Figure 3 is a view similar to Figure 2, the channel entrance and its mounting being ²⁵ shown, however, shifted from the position shown by the full lines in Figure 2 to one of its inoperative positions shown by the full lines in Figure 3.

Figure 4 is a fragmentary view showing ³⁰ a portion of the channel entrance mounting and its support, the channel entrance being shown shifted to another inoperative position which it may assume.

Figure 5 is a rear elevation of the upper ³⁵ portion of a typographical machine of the class hereinbefore referred to but having an auxiliary or side magazine unit combined therewith, the improved channel entrance and mounting embodying the present invention ⁴⁰ being shown applied to both the main and side units of the machine.

Figure 6 is a detail sectional view, the section being taken on the line 6—6 of Figure 5.

Figure 7 is a detail sectional view, the section being taken on the line 7—7 of Figure 5.

Figure 8 is a detail sectional view, the section being taken on the line 8—8 of Figure 5.

In the embodiments of the invention shown in the accompanying drawings, 10 designates the distributor bracket and 11 designates the usual distributor bar to which ⁴⁵ the usual distributor rails are attached and 12 designates the distributor screws which operate upon the matrices to advance them along the distributor rails while suspended therefrom until they reach their appropriate channels in the magazines, as is well under-

stood in this art. The distributor partly shown is of the double type to enable matrices belonging to two or more magazines to be distributed thereto. In the present instance, two magazines, 13 and 14, are supported in superposed relation on a frame or cradle 15, the magazines being shown in Figure 1 in their normal forwardly and downwardly inclined operative position. The distributor brackets carry or have fixed thereto brackets 17 and 18 which serve to support the channel entrance or entrances, these brackets being shown secured to the distributor bracket by screws 19. These brackets 17 and 18 are provided with bearings 20 in which the channel entrance mounting is supported.

A pair of channel entrances 24 and 25 are provided for guiding the matrices from the distributing mechanism to the respective ²⁵ magazines 13 and 14, the channel entrances containing partitions 26 which receive the matrices between them and maintain them in upright position while descending through these entrances.

As shown by the full lines in Fig. 1 and the dotted lines in Fig. 2, the upper ends of the entrances, when in operative position, project upwardly above the bottoms of the lower distributor screws, and in order to ²⁵ secure a downward movement of the entrances which will insure clearance between their upper ends and the distributing mechanism when the entrances are swung rearwardly or into inoperative position, a composite mounting is provided which comprises pivotally connected frame members 27 and 28. The frame member 28 comprises links which are suitably spaced and provided with pivots 29 which engage in the ¹⁰⁵ bearings 20 in the stationary brackets 17 and 18. The composite mounting of the channel entrances is adapted to swing as a whole about the pivots 29, and in order that this movement of the channel entrances may be rearwardly and then downwardly, the pivots 29 are located approximately directly below the distributing mechanism. The frame 27 is pivoted on the frame 28 so that these frames may have a relative pivoting movement. As shown, the frame 27 is provided at its sides with pivots 30 which engage in bearings 31 formed in the links comprising the frame 28. The frame 27 rocks or swings on the centers of the pins 30 during the movement of the channel entrances which lowers them from operative relation with the distributing mechanism, and in order to secure a sharp downward movement of the channel entrances which will avoid interfering with or interference from the distributor mechanism, the pivots 30 and their bearings 31 are located forwardly of the pivots 29 about which the channel entrance mounting as a whole swings, and preferably

¹¹⁵
¹²⁰
¹²⁵
¹³⁰

the pivots 30 and their bearings 31 are located in a vertical plane which is forward of the distributing mechanism whereby the upper ends of the channel entrances in 5 swinging from their normal operative position shown by the dotted lines in Fig. 2 to the full line position shown in that figure will describe the arc T which clears the lower rear distributor screw. The frame 27 10 preferably embodies end members 32 and 33 which are rigidly connected by a longitudinal rail or brace 34. Adjustable screws 40 are threaded into the forward upper ends of the links and the heads of these screws form 15 abutments on which the forward ends of the end members 32 and 33 of the frame member 27 may come to rest, thus limiting the forward swing of the frame member 27 about the pins 30 as centers. These set 20 screws may be locked in adjusted position by jamb nuts 41. The rear upper ends of the links 28 comprising the lower frame are formed with abutment surfaces 42 which are adapted to be engaged by the abutment surfaces 25 43 on the end members 32 and 33 of the frame 27, thus limiting the downward and rearward swing of the frame 27 as shown by Fig. 2 wherein the abutment surfaces 32 and 43 are in engagement.

30 The channel entrances are so mounted in the frame member 27 as to enable them to accommodate themselves to the positions occupied by the upper ends of the magazines to which they pertain. For this purpose, 35 the end members 32 and 33 of the frame 27 are formed with upwardly extending arms 45 and these arms are provided with apertures 46 in which are fitted aligned pivots 47 and 48, as shown in Fig. 5. The pivot member 47, as shown in Fig. 6, is secured 40 against longitudinal displacement from the finger 45 by a set screw 49 which is threaded into the arm and engages at its inner end in an annular groove 47^a which is formed at the middle of the pivot member 47. Bars 45 50 and 51 are secured to the rear walls of the channel entrances 24 and 25, respectively, and these bars are connected to the pivot members 47 and 48 by arms 52 and 53 which 55 are attached to the bars 50 and 51, respectively. The pivot-engaging ends of the arms 52 and 53 are preferably formed with hooks 54 and 55, respectively, the hooks 54 on the bar 50 engaging the inner ends of the pivots 47 and 48 and the hooks 55 on the bar 51 60 engaging the outer ends of the pivots 47 and 48. The pivot 47 is preferably threaded while the pivot 48 may be unthreaded, and the hook 54 is threaded on the inner threaded portion of the pivot 47 so that rotation of this pivot will adjust the hooks 54 axially on the pivots 47 and 48. Also, the pivot 47 has a threaded engagement with an adjusting sleeve 56 which has a grooved periphery to 65 receive the hook 55 whereby the hooks 55 may be adjusted axially of the pivots 47 and 48. By this construction, the channel entrances are pivotally secured to the frame 27 so that the forward ends of the channel entrances may rock and thus accommodate 70 themselves to the vertical positions of the upper ends of the respective magazines, and also the channel entrances may be adjusted laterally and individually in the frame 27 to insure proper lateral registration between 75 the entrances and the respective magazines.

The channel entrances are reinforced by 80 bars 60 and 61 which are secured to their rear walls toward the forward ends thereof. The ends of these bars extend outwardly beyond the sides of the respective channel entrances and are positioned between abutment surfaces or stops 62 and 63 which are formed on the end members 32 and 33 of the frame 27, these abutment surfaces or stops limiting 85 the pivotal movements of the channel entrances about the pivot members 47 and 48. The ends of the bar 60 are pressed upwardly against the abutting surfaces 63, while the entrances are removed from operative position by compression springs 64 which are located in the end members 32 and 33 beneath the bar 60, but the ends of the rail 61 will rest by gravity on the lower abutment surfaces 62 when the upper channel entrance 90 is removed from operative relation with its magazine.

In order to hold the channel entrances and 95 their mounting in operative position and to counter-balance the weight of these parts and thus facilitate manipulation thereof, tension springs 65 are provided, these springs being attached at one end to sleeves 66^a swivelled on the screws 66 on the frame 27 and to sleeves 67^a swivelled on the screws 100 105 67 on the distributor bracket 10. These springs act to move the channel entrances into operative position and to maintain them in normal operative relation with their magazines. The screws 66 and 67 to which the 110 springs are attached are out of line with and above the pivots 30 when the channel entrances are in or near operative position, as will be understood from Figs. 1 and 2, and these springs will, therefore, act to swing the frame 27 upwardly and forwardly about the pivots 30, thus carrying the forward ends of the channel entrances toward the upper ends of the magazines until such motion is 115 arrested by the engagement of the frame 27 with the limit or stop screws 40. Also, these springs act on a line which is above the pivots 29 of the frame 28, and, hence, they tend to swing the frame 28 forwardly about the pivots 29, as will be clear from Figs. 2 and 120 3. The springs, therefore, tend to swing the frame 28 from its rearward position shown in Fig. 3 to its forward position shown in Fig. 2, and in order to arrest the forward 125 motion of the frame 28, the brackets 17 and 130

18 are provided with adjustable set screws or limit stops 68 against which the under sides of the links comprising the frame 28 are adapted to abut. These set screws may be locked in appropriately adjusted positions by jamb nuts 69.

In order to insure proper registration between the forward end of the channel entrance 25 and the upper end of its magazine 13 as this channel entrance is swung into operative position, guide fingers 70 are secured to the opposite ends of the reinforcing bar 61 on this channel entrance, these fingers being provided with bevelled surfaces 71 which are adapted to engage the upper surface of the magazine 14 and ride upon such surface while the channel entrance 25 is moving into operative relation with its magazine, these guide fingers thus insuring proper vertical registration between this channel entrance and its magazine. Also, to insure proper vertical registration between the lower channel entrance 24 and its magazine 13, a guide lip 72 is secured to the rear wall of the channel entrance 24 and projects forwardly beyond the front end of this channel entrance, this guide lip being adapted to engage the lower surface of the lower magazine 13 as the channel entrance 30 is moving into operative position. The bar 61 of the upper channel entrance 25 rests on the surface 62 by gravity and the bar 60 of the lower channel entrance is pressed against the upper surface 63 by the spring 35 64 while the channel entrances are removed from operative position, as will be clear from Fig. 2, but as the guide fingers 70 ride upon the upper surface of the respective magazine, during the swing of the upper channel entrance into operative position, the bar 61 will be free to rise from the surface 62 under the control of the guide fingers 70; and also, as the guide lip 72 on the lower channel entrance abuts against the under side of the magazine 13 during the movement of this channel entrance into operative position, the bar 60 on the lower channel entrance may be retracted from the abutment surface 63 against the action of the spring 64 under control of the guide lip 72.

Means is provided whereby the channel entrances and their mounting may be swung into either of two inoperative positions, at will. To secure this result, a stop 75 is provided, this stop being pivoted on a screw or other suitable pivot 76 attached to the frame member 17 and having a finger-piece 78 by means of which it may be swung by hand to occupy either the full or dotted line position shown in Figure 5. The stop has a lug 79 thereon which is adapted to rest on the surface 80 on the frame member 17 when the stop is in its full line position, and the lug 79 will then be in a position to be engaged by the abutment surface 81 on the rear

of the adjacent link of the frame 28. With the stop in this position rearward swing of the entrances and their mounting will be arrested when the parts reach the position shown by the full lines in Figure 3, this movement taking place about the pivots 29 so that the upper portion of the channel entrances swings through the arc U, Fig. 3. As the upper end of the magazine 13 in swinging rearwardly about the pivot 16 moves through the arc P, Figure 3, it will be clear that when the entrances and their mounting have been swung to the position shown in Figure 3, they will clear the upper ends of the magazines when the latter are 80 swung rearwardly into magazine removing position, and vice versa. However, when it is desired to secure greater access to the distributing mechanism or the channel entrances, or to discharge any matrices that 85 may have clogged within the channel entrances, or either of them, the stop 75 is swung into the dotted line position shown in Figure 5 before the channel entrances are swung to inoperative position, and then the 90 rearward and downward swing of the channel entrances and their mountings to inoperative position may continue past the full line position shown in Figure 3 to the 95 position shown in Figure 4, as the movement of the channel entrances and their mounting is then not arrested until the abutment surface 81 on the frame 28 reaches the abutment surface 80 on the frame member 17. When the channel entrances reach the 100 position shown in Figure 4, the distributing mechanism and the channel entrances are easily accessible, and, furthermore, the channel entrances are brought to an inverted upright position to cause any matrices that 105 may have clogged therein to discharge by gravity therefrom. To facilitate swinging of the channel entrances to and from operative position, a handle 82 is fixed to the frame 27 of the channel entrance mounting, 110 this handle serving as means for manipulating the channel entrances.

The structure thus far described enables the channel entrances to be easily and quickly removed from operative relation with the 115 distributing mechanism, disconnected from the magazines and swung into an inoperative position where they will be clear of the magazines when the latter are swung rearwardly for removal or changing of magazines, and the channel entrances may be easily and quickly restored to operative position. When it is desired to swing the magazines rearwardly into magazine removing position, the handle 82 is first grasped and pulled downwardly. This operation rocks the frame 27, together with the channel entrances thereon in a direction downwardly and rearwardly about the pivot 30 while the frame 28 still rests on the stops 68. The 120 125 130

channel entrances are thereby carried from the position shown in Figure 1 or by the dotted lines in Figure 2 into the full line position shown in Figure 2 through the arc 5 designated T, this relatively sharp downward movement of the channel entrances enabling their upper ends to clear the lower distributor screws and at the same time detaching the forward ends of the channel 10 entrances from the upper ends of the respective magazines. This downward and rearward movement of the frame 27 continues until the abutment surface 43 thereon reaches the abutment surface 42 on the frame 28, 15 whereupon a continued downward pull on the handle 82 will cause the frames 27 and 28 to swing in unison in a rearward and downward direction about the pivots 29, through the arc designated U in Figure 3, so that the 20 channel entrances and their mounting move from the position shown by the full lines in Figure 2 to the full line position shown in Figure 3. While the channel entrances and their mounting occupy this latter position, 25 the magazines may be swung or rocked rearwardly into a position to permit the magazines thereon to be removed at the rear of the machine. After the magazines have been restored to their normal position, as shown 30 in Figure 1, the magazine entrances and their mounting are returned to operative position by a reversal of the operations just described, the frames 27 and 28 first swinging in unison upwardly and forwardly about the 35 pivots 29 and finally the frame 27 swinging forwardly and upwardly about the pivots 30, the upper ends of the channel entrances being thus restored to operative relationship 40 with the distributing mechanism and the forward ends of the channel entrances re-establishing operative relationship with the upper ends of the respective magazines. The springs 65 act to hold the channel entrances in their normally operative 45 position and they also serve to counterbalance the channel entrances and their mounting, thus enabling the operator to swing the channel entrances to and from operative position with greater ease and 50 facility. These springs also act to hold the abutment surfaces 42 and 43 of the frames 28 and 27 in engagement after the pivots 30 connecting these frames have passed above the plane in which these springs act and, 55 hence, during the return of the channel entrances to operative position, their upper ends will swing through the arc U, thus insuring clearance between the channel entrances and the lower rear distributor screw 60 during the return of the channel entrances to operative position. Preferably, the weight of the channel entrances and their mounting is so distributed with respect to the strength 65 and action of the springs 65 to cause the channel entrances and their mounting to rest

by gravity in either of the two inoperative positions shown in Figures 3 and 4.

The channel entrances and their mounting have been hereinbefore described as applied to the main magazines of the machines, but 70 when it is desired to apply such channel entrances to a machine which embodies a so-called side magazine unit containing auxiliary magazines 13' and 14', an extension frame member 27' is attached to the frame 75 27 as, for example, by screws 86 which secure lugs 87 on the extension frame member 27' to similar lugs 88 which may be formed on the frame 27 so that the extension frame member 27' for the side magazine unit becomes, in effect, a part of the frame 27. This construction enables a side magazine unit to be applied to the main unit of the machine equipped with channel entrances 80 embodying the present invention and enables the improved channel entrances to be applied to the side magazine unit without altering the operation of the main unit of the machine. The extension frame member 27' 85 may be provided with a leg 89 having a laterally projecting pivot pin 90 thereon, this pivot pin being arranged to enter a seat formed in a lug 91 carried by an arm 92 attached to a part of the stationary frame of the machine. With this arrangement, the pivot pin 90 will enter and rest in the seat in the lug 91 when the channel entrances are moved to their operative position, the arm 92 then assisting in sustaining the weight of the extension frame member 27' and thus insuring proper relationship between the channel entrances and the distributing mechanism 95 and the magazines.

In machines of this general class, means is usually provided for automatically interrupting the operation of the distributing mechanism when the channel entrance is removed from its normal operative position or when a matrix becomes jammed between the distributor screws and a partition of the channel entrance. The present invention enables such automatic stopping means to be accommodated between the channel entrances. As shown, a space is provided between the adjacent upper edges of the channel entrances 24 and 25 in which is mounted longitudinally disposed automatic stop bars 93 and 94, the bar 93 being supported by the entrances for the main magazines and the bar 94 by the entrances for the side unit magazines. The adjacent or inner ends of these bars abut, and the bar 94 and by it the bar 93, are yieldingly held in the right-hand position by a tension spring 95 which is connected to the bar 94. Each bar is provided with fingers 96 which are spaced to conform with the spacing of the flexible channel entrance partitions 23, the fingers projecting laterally from the upper edge of the bar 100 and engaging ears 97 formed on the upper 105 110 115 120 125 130

proximate edges of the channel entrance partitions. By this arrangement if one of the channel entrance partitions is moved toward the left in Fig. 5 by a matrix becoming jammed between it and the distributor screws, the bars 93 and 94 will be correspondingly moved, and this movement of the bars will bring the slot 98 in the bar 94 into registration with the finger 99 carried by a rocker 100. This rocker is a part of the well-known automatic distributor clutch mechanism and it functions in a manner well understood by those skilled in the art. When the finger 99 registers with the slot 98 it enters said slot, thus permitting the lug 101 on the rocker to move into the path of the cam 102 mounted on the constantly revolving shaft 103 of the usual distributor clutch mechanism, this engagement of the lug 101 with the cam 102 causing the clutch mechanism 104 to interrupt the drive of the distributor. By mounting the automatic step bars between the channel entrances, the fingers 96 on the upper edges of these bars may act in common for the partitions 23 of the front and rear channel entrances, thereby enabling one bar to serve for both entrances. It will be understood that when the channel entrances are removed from their operative position, the bar 94 will be removed from the lug 99 and the distributor driving clutch will be automatically disengaged in a manner which is well understood in this art.

33 While the invention has been illustrated and described as applied to a machine of the so-called "mixer" type, containing two matrix magazines, it will be understood that it is also applicable to machines of the type 40 containing either a single magazine and the usual single type of distributor or containing more than two magazines.

By mounting the channel entrance or entrances on a pair of frames which are pivoted 45 for movement relatively to one another and also in unison about the center as hereinbefore described, the operations of swinging the entrances to and from operative position are greatly facilitated, as the first movement 50 of the entrances will be in a downward and rearward direction which will lower the entrances out of operative relation with the distributor and will withdraw the entrances from the upper ends of the magazines, and the subsequent rearward and downward movement of the entrances will carry them 55 out of a position beneath the distributor to a position which renders the distributor and the entrances readily accessible and which 60 enables the magazines to be rocked rearwardly into magazine removing position without interference from the entrances.

I claim as my invention:—

65 1. In a typographical machine of the class embodying a matrix magazine, a matrix dis-

tributor, and a channel entrance arranged between the magazine and the distributor, a mounting for the channel entrance which is operative to first lower the channel entrance to remove it from operative relation 70 with the distributor and is subsequently operative to carry the channel entrance rearwardly from beneath the distributor and downwardly.

2. In a typographical machine of the class 75 embodying a matrix magazine, a matrix distributor, and a channel entrance arranged between the magazine and the distributor, a mounting for the channel entrance comprising cooperative frames one of which carries the channel entrance and is movable to lower the channel entrance and thus remove it from operative relation with the distributor, and another of which frames is movable to carry the channel entrance rearwardly out of its operative position beneath the distributor.

3. In a typographical machine of the class 80 having a matrix magazine, a matrix distributor, and a channel entrance between the magazine and distributor, a mounting for the channel entrance comprising a pair of cooperative pivotally connected frames one of which is movable relatively to the other to carry the entrance downwardly about a 85 center located in front of the distributor, and the other frame being movable to carry the channel entrance and the first-mentioned frame out of a position beneath the distributor.

4. In a typographical machine of the class 90 having a matrix magazine, a matrix distributor, and a channel entrance between the magazine and distributor, a mounting for the channel entrance operative to move the entrance first rearwardly and downwardly 105 to withdraw the entrance from the magazine and lower the entrance from the distributor and subsequently operative to carry the entrance rearwardly away from the magazine and distributor.

5. In a typographical machine having a matrix magazine, a matrix distributor, and a channel entrance between the magazine and distributor, a mounting for the entrance 110 comprising a pair of cooperative pivotally connected frames one of which carries the channel entrance and is pivoted to the other frame at a point so located as to lower or raise the entrance when the first-mentioned 115 frame is moved relatively to the other frame, and said other frame being pivotally supported whereby both of said frames may 120 swing in unison to carry the entrance from a position beneath the distributor.

6. In a typographical machine having a matrix magazine, a matrix distributor, and a channel entrance adapted to occupy a position 125 between the distributor and the magazine for directing matrices from the former 130

to the latter, a mounting for the channel entrance comprising a frame having the channel entrance pivotally mounted thereon, and a second frame pivotally connected to the first-mentioned frame, the first-mentioned frame being movable in a direction which will raise or lower the channel entrance relatively to the distributor and carry the entrance to and from operative relation with the magazine while the second-mentioned frame remains stationary, and the latter frame swinging in unison with the first-mentioned frames about a pivotal center which will remove the entrances from a position beneath the distributor.

7. In a typographical machine having a matrix magazine, a matrix distributor, and a channel entrance for directing matrices from the distributor to the magazine, a mounting for the channel entrance having pivots on which said entrance is pivoted and on which the entrance is movable laterally, the entrance being adapted to engage the magazine and thereby adjust itself, the mounting being operative to carry the entrance to and from operative relation with the magazine and distributor.

8. In a typographical machine having a matrix magazine, a matrix distributor, and a channel entrance between the distributor and magazine, a mounting for said entrance comprising a frame pivotally mounted on a support, a second frame pivotally mounted on said first-mentioned frame and carrying the channel entrance, and means acting on said second frame to yieldingly hold it in one position relatively to the first-mentioned frame to maintain the entrance in operative relation with the magazine and distributor when the first-mentioned frame occupies one position and for holding said second frame in another position relatively to the first-mentioned frame when the latter is swung on its pivot to carry the entrance out of its operative position.

9. In a typographical machine having a matrix magazine, a matrix distributor, and a channel entrance between the distributor and the magazine, a mounting for said entrance comprising a frame carrying the entrance, a second frame on which said entrance-carrying frame is pivoted and having a pivotal support, and a spring acting on the entrance-carrying frame to swing it away from the second frame and thereby hold the entrance in operative relation with the distributor while the second frame occupies one position and to swing the entrance carrying frame against the second frame and hold it in such relation while the second frame occupies another position, said spring also acting to counterbalance the entrance and its mounting when swung out of operative position.

10. In a typographical machine having a matrix magazine, a matrix distributor, and a channel entrance between the distributor and magazine, a mounting for the entrance pivoted to swing the entrance from an operative position to either of two inoperative positions, and a controlling stop capable of being set to determine which of said inoperative positions will be assumed by the entrance.

11. In a typographical machine having a plurality of matrix magazines, a matrix distributor, and channel entrances between the respective magazines and the distributor, a mounting for said entrances comprising a frame supporting said entrances for limited individual movement to adjust them to their respective magazines, said frame being pivoted to swing the entrance to and from a position in which the entrances are in operative relation with the distributor and the respective magazines.

In testimony whereof I have hereunto set my hand.

JOHN ROBERT TOMLIN.
